John S. Parker ^{Attorney}

UNITED STATES PATENT OFFICE.

CHARLES F. BALL, OF MILWAUKEE, WISCONSIN, ASSIGNOR TO CHAIN BELT COMPANY, OF MILWAUKEE, WISCONSIN, A CORPORATION OF WISCONSIN.

ADJUSTABLE SUPPORT FOR LOADING SKIPS.

Application filed May 31, 1927. Serial No. 195,301.

My invention relates to a support for a loading skip of a concrete mixing machine or similar apparatus, and has for its object to mount such support so that it may be folded or caused to occupy a position different from that normally occupied when the skip is in use, and to provide means whereby the moving of the support from one position to another may be controlled from the power shaft 5 from which the movements of the skip are controlled.

In the accompanying drawings, in which one embodiment of my invention as applied to a street paver is illustrated,

Fig. 1 is a side elevation of a machine embodying the invention.

Fig. 2 is a transverse sectional view taken on the line II—II of Fig. 1.

Fig. 3 is a sectional view on the line III—III of Fig. 2, and

Fig. 4 is a cross-sectional view on the line IV—IV of Fig. 2.

Referring to these drawings, 2 designates the mixing drum supported in well known or preferred manner in the framework of a road-paving machine. The detail parts of such apparatus are not illustrated, as Fig. 1 in many respects is diagrammatic, and it is to be understood that such drawing is merely sufficient to illustrate one embodiment of my invention, and is typical, my invention being adapted for use in connection with other machines than those intended for mixing concrete.

3 indicates a loading skip of well known construction, pivotally supported so as to occupy either the lowered position indicated in full lines for receiving its load, or an elevated position, indicated by dotted lines, for discharging into the mixing drum.

4 indicates the skip-lifting cables, and 5 the drums on which the cables are wound. These drums are secured to a shaft 6, at one end of which is a bull wheel 7 on which is wound a cable that extends to a power-driven winding drum 9 which, so far as the present invention is concerned, may be considered the primary power element of the skip-moving-and-controlling mechanism.

50 The cross shaft 6 is supported in a pair of

pivoted uprights 10 formed at their lower ends into foot pieces 11 adapted to rest upon suitable seats formed therefor on the main framework of the machine, the uprights 10 being pivotally connected to such framework 55 at 12. The upright supports are normally held in inclined positions, with their feet pieces securely resting upon the seats, by brace pieces 21, which have pivotal connections at 22 with the framework of the apparatus. The shaft 6 extends through a sleeve or tube 13 supported in the bearings 20 at the upper ends of the pivoted pieces 10, being supported so as to be free to turn in suitable bearings 23 located within the sleeve or tube. 60 At the end of the sleeve 13 toward the bull wheel, there is a bracket 15 carrying a seat or housing 16 for a slide bolt 14, the end of which, when the bolt is moved outwardly, is adapted to enter a socket 17 formed in the 65 hub of the adjacent drum 5, and thus lock the said drum and the shaft to which it is secured against rotation, since the seat for the slide bolt is a part of the framework of the machine. The bolt 14 is provided with a projecting pin sufficiently long to serve as a handle by which the bolt is manipulated, and which it is arranged to move in the slot 18 and to hold the bolt in either its retracted or its projected position.

Under normal conditions of use the parts occupy the positions indicated in full lines in Fig. 1, with the supports 10 in raised position, and with the slide bolt 14 retracted, leaving the shaft 6 and the drum and wheel which it 70 carries free to turn. The parts are securely held in these positions by the brace pieces 21. Under such conditions the skip may be raised and lowered by driving the shaft 6, through the power cable 8 and bull wheel 7, and rotating the drums either to wind the cables thereupon to raise the skip or paying out such cables when the skip is to be lowered. These movements are well known in the art and need no further description.

It frequently happens that it is desirable to let down or fold the skip-supporting parts in order to reduce the height of the apparatus. To accomplish this without disconnecting any of the cables that have been described, and 100

at the same time permitting the movements of the parts, which are quite heavy, to be controlled from the winding drum 9 for the power cable, the novel features of my invention are brought into operation. When the skip-supporting parts are to be lowered from the position indicated in full lines Fig. 1 to that represented by dotted lines, the slide bolt 14 is moved outwardly and caused to enter the socket 17 in the hub of one of the winding drums 5. When this has been effected the wheel 7 is locked against rotation. If, now, the drum 9 be turned to pay off the power cable 8 therefrom, the frame carrying the shaft 6 will move downwardly upon its pivots, provided the braces 21 have first been disconnected from the frame to allow the supports to move. It will thus be seen that the skip support may be lowered or raised by means of the power cable 8, thus entirely eliminating the heavy manual labor that has heretofore been required to effect either the lowering or raising of the pivoted skip support. I have shown one means for locking or preventing the rotation of the shaft 6, such means being the one which I found most expedient to employ, but my invention is not limited to the specific arrangement of parts shown, all that is necessary for accomplishing the advantageous features of my invention being the locking of the wheel 7 with which the power cable engages from free rotation. And when this has been accomplished the support for such cable will be lowered whenever the cable 8 is let off from its winding drum 9, or raised to normal working position when wound thereon.

It will be understood that the cables 4 and the drums 5 on which they are wound are elements of power driven mechanism for controlling the up and down movements of a piece of apparatus to be moved, such as the skip 3; and that the cable 8 and the drum 9 on which it is wound constitute elements of power driven gearing or mechanism that operate the gearing just referred to for directly moving the part 3; and while in the drawings there is illustrated a specific form of such mechanism especially devised for use in controlling the movements of a loading skip for concrete mixing machines, it is to be understood that the invention is not restricted to details of construction nor beyond the limitations imposed by the claims hereof.

What I claim is:

1. The combination, with a loading skip, a cable for operating it, a winding drum for the cable, a pivoted support for the cable drum, and means for turning the drum to wind up or let off the skip cable, including a power-driven cable; of releasable means for holding the pivoted support in normal working position and means for preventing the turning of the skip cable drum, while per-

mitting the power cable to be operated, 65 whereby the pivoted support is moved, upon being released from its holding means, as the power cable is wound up or let out.

2. The combination, with a loading skip, a cable for operating it, a winding drum for 70 the cable, a pivoted frame for the cable drum, and means for turning the drum to wind up or let off the skip cable, including a power-driven cable; of releasable means for holding the pivoted frame in normal working position and means for locking the skip cable 75 drum to a non-rotating part of the pivoted frame, whereby, upon releasing of the supporting frame from its holding means, operation of the power cable causes movement of 80 the supporting frame about its pivot.

3. The combination of a loading skip, cables for operating it, winding drums for the skip cables, a pivoted frame for the cable drums whose normal position is inclined, 85 whereby if unsupported it moves downward about its pivot, bracing means for holding the supporting frame in normal inclined position, such bracing means being disconnectable to relieve the pivoted frame of the support afforded thereby means for turning the drums to wind up or let off the skip-moving cables, including a power-driven cable and its winding drum, and means for preventing the turning of the drums on which are wound the skip-moving cables while permitting the power cable and its drum to operate, whereby when the said bracing means are disconnected and the power cable is let off its drum the pivoted frame moves downwardly under the control 100 of the power cable and when the cable is wound upon its drum the frame is raised.

4. The combination of a loading skip, cables for operating it, a pivoted supporting frame that normally occupies an inclined position, comprising a pair of supports, a shaft mounted in said supports so as to turn, drums on which the skip-moving cables are wound mounted on said shaft, separable bracing means for holding the supporting frame in 105 inclined position, means for turning the shaft and drums which it carries, including a power cable, a power-driven drum on which one end of the power cable is wound, and a wheel supported on the said shaft on which the other end of such cable is wound and a slide bolt uniting one of the skip cable drums with a part of the pivoted frame whereby rotation 110 of the skip cable drums and their supporting shaft is prevented and the supporting frame 115 is raised or lowered by operation of the power cable, upon its being released from the holding action of the said bracing means.

5. The combination with a piece of mechanism to be raised and lowered, power driven 125 gearing by which such movements are imparted, including a rotatable element, a train of power driven gearing through which the

said rotatable element is turned, a support for the said rotatable element movable when free from a normal working position to a folded or abnormal position, such movements being controlled by the power driven mechanism that operates the rotatable element and without disturbing the connection between

the rotatable element and the piece of mechanism to be moved, manually operated means for locking the rotatable element against rotation in its support and means by which the support may be positively held in its normal position or released for free movement at will. 10

CHARLES F. BALL.
